(57) **CLAIM**

The ornamental design for an arrow shaft grinder, as shown and described.

DESCRIPTION

FIG. 1 is a perspective view of an arrow shaft grinder embodying my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top and front perspective view thereof in a state of use; and, FIG. 9 is a bottom and front perspective view thereof in a state of use.

The broken lines in FIGS. 8 and 9 represent the environment only and form no part of the claimed design.

1 Claim, 5 Drawing Sheets
